(57) **CLAIM**

The ornamental design for an articulating contact pin, as shown and described.

DESCRIPTION

FIG. 1 is a front perspective view of a first embodiment of an articulating contact pin showing our new design;

FIG. 2 is a rear perspective view thereof;

FIG. 3 is a side elevation view thereof with the other side being a mirror image thereto;

FIG. 4 is a rear elevation view thereof;

FIG. 5 is a front elevation view thereof;

FIG. 6 is a bottom plan view thereof;

FIG. 7 is a top plan view thereof;

FIG. 8 is a front perspective view of the upper pin portion of the first embodiment of an articulating contact pin thereof;

FIG. 9 is a rear perspective view thereof;

FIG. 10 is a side elevation view thereof with the other side being a mirror image thereto;

FIG. 11 is a rear elevation view thereof;

FIG. 12 is a front elevation view thereof;

FIG. 13 is a bottom plan view thereof;

FIG. 14 is a top plan view thereof;

FIG. 15 is a front perspective view of a second embodiment of an articulating contact pin showing our new design;

FIG. 16 is a rear perspective view thereof;

FIG. 17 is a side elevation view thereof with the other side being a mirror image thereto;

FIG. 18 is a rear elevation view thereof;

FIG. 19 is a front elevation view thereof;

FIG. 20 is a bottom plan view thereof;

FIG. 20 is a top plan view thereof;

FIG. 22 is a front perspective view of upper pin portion of the second embodiment of an articulating contact pin thereof;

FIG. 23 is a rear perspective view thereof;

FIG. 24 is a side elevation thereof with the other side being a mirror image thereto;

FIG. 25 is a rear elevation view thereof;

FIG. 26 is a front elevation view thereof;

FIG. 27 is a bottom plan view thereof; and,

FIG. 28 is a top plan view thereof.

The broken line in the figure drawings is included to show the unclaimed subject matter only and forms no part of the claimed design. The dash-dot line represents the boundary of the claimed design.
